[57] CLAIM

The ornamental design for a telephone cord rotary connector, as shown and described.

DESCRIPTION

FIG. 1 is a perspective view of a telephone cord rotary connector showing my new design;

FIG. 2 is a top plan view thereof;

FIG. 3 is a right side elevational view thereof;

FIG. 4 is a bottom plan view thereof;

FIG. 5 is a front elevational view thereof;

FIG. 6 is a rear elevational view thereof;

FIG. 7 is a perspective view of a second embodiment of a telephone cord rotary connector showing my new design;

FIG. 8 is a top plan view thereof;

FIG. 9 is a right side elevational view thereof;

FIG. 10 is a bottom plan view thereof;

FIG. 11 is a front elevational view thereof; and,

FIG. 12 is a rear elevational view thereof.

FIG. 5**FIG. 6****FIG. 7****FIG. 11****FIG. 12****FIG. 8****FIG. 9****FIG. 10**
